(57) CLAIM

The ornamental design for a razor handle, as shown and described.

DESCRIPTION

FIG. 1 is a top plan view of a razor handle showing my new design;

FIG. 2 is a bottom plan view thereof;

FIG. 3 is a front elevational view thereof;

FIG. 4 is a left side elevational view thereof, the right side being a mirror image;

FIG. 5 is a first perspective view thereof;

FIG. 6 is a second perspective view thereof; and,

FIG. 7 is a third perspective view thereof.

FIGS. 1-3 show the razor handle on its own. FIGS. 4-7 show the razor handle with a cartridge attached to it. The cartridge and certain parts of the razor handle, which are shown in dotted lines, do not form part of the claimed design.
